SELF-RELEASING LOCK CONTROL

Max Sultan, Brooklyn, N. Y.

Application September 16, 1950, Serial No. 185,241

2 Claims. (Cl. 292—359)

1

This invention relates to door latches.

It is an object of the present invention to provide a door latch wherein the door can be locked from the inside of the room to render access to the room from one on the outside of the room impossible until the knob is turned from the inside of the room and wherein the turning of this knob automatically releases the locking element as when one is leaving the room.

Other objects of the present invention are to provide a door latch with an inside lock which is of simple construction, inexpensive to manufacture, has a minimum number of parts, is compact, easy to operate and efficient in operation.

For other objects and for a better understanding of the invention, reference may be had to the following detailed description taken in connection with the accompanying drawing, in which

Fig. 1 is a perspective view of a complete door handle assembly embodying the features of the present invention.

Fig. 2 is a collective and perspective view of the parts of the door handle assembly mounted at one side of the door and including the press button lock parts.

Fig. 3 is a fragmentary transverse section of the door handle assembly taken generally on line 3—3 of Fig. 1.

Fig. 4 is a fragmentary sectional view similar to Fig. 3 showing only a part of the assembly with the press button pushed in and retained by the operating member to prevent the turning of the handle shaft from the outer side of the door.

Fig. 5 is a fragmentary transverse sectional view taken generally on line 5—5 of Fig. 3 with the parts being in position to permit the free turning of the handle on the outer side of the door.

Fig. 6 is an enlarged sectional view taken on line 6—6 of Fig. 4.

Fig. 7 is a fragmentary sectional view of the operating parts illustrating the manner in which the vertically adjustable operating member is moved downwardly to release the push button and to render the knob on the outside of the door free to be turned again.

Referring now to the figures, 10 represents a door in which is mounted the usual door latch assembly 11 having a latch element 12 adapted to enter a slotted plate in the door frame and which, within the door, is adapted to receive a square operating shaft 13 of a door handle assembly indicated generally at 14. The latch assembly is made secure within an opening in the door body by screws 15.

2

The door handle assembly 14, in addition to the shaft, includes a door knob 16 disposed on the outer side of the door and a door knob 17 on the inner side of the door. The shaft 13 is set in an opening in the knob 17 and passes into a square opening 19 of the knob 16. This knob 16 carries on its inner end a closure plate 21. The shaft 13 within the door 10 passes through a square opening of an operating member of the latch assembly 11 so that as the shaft 13 is turned by either of the handles, the latch element 12 may be operated.

On the inner side of the door is a rosette or cover plate 25 having a flange that enters groove 26 of the door knob 17. Screws 23 and 24 secure the rosette in position.

The set screw 18 secures the knob to a sleeve piece 27 that is threaded into the knob and which receives the round portion of the shaft 13. The rounded portion of the shaft 13 is indicated at 13' and is moveably secured to the flanged end of the sleeve piece 27 by a transverse pin 27a, and said pin is disposed opposite cam 28, in a loose fitting keyway located in the flange portion, thereby allowing the sleeve 27 to rotate an amount equal to the play between the pin and the walls of the keyway. This play is sufficient to have the cam depress element 34 thereby permitting projection 42 of element 41 to rotate with the shaft a limited angle free from hitting element 35's abutments.

The sleeve piece 27 has a flanged disc having an integral projecting cam portion 28 with inclined opposite faces 29 and 30 adapted to act upon edges 31 and 32 of a vertical slide member 33. The vertical operating member has side projections 34 and 35 at the opposite sides thereof. The closure plate 25 has transversely spaced guide portions or ribs 36 and 37 for guiding the transverse movement of the operating member 33 and for retaining in the ends thereof respective springs 38 and 39. One end of each of the springs 38 or 39 reacts against the projection 34 of the operating member 33 and against a projection 40 of a guide portion 36 or 37 to urge the operating member 33 upwardly. The guide projection 40 serves as a stop against which projection 35 of the operating member 33 engages to limit the upward movement of the operating member. On the shaft 13 is a square opening member 41 having a depending projection 42 adapted to pass through opening 43 in the lower end of the operating member 33. Normally, this projection 42 is free of the opening 43, as shown

in Fig. 5, whereby to permit the turning of the knobs.

A channeled retaining plate 44 fits over the operating member, the squared opening member 41 and the springs 38 and 39 and into the cover plate 25 whereby to retain these parts in coupled relationship and proper positions. This retaining plate is held in place by two rivets 45 extending through the plates at the opposite sides thereof.

This retaining plate 44 carries a sleeve 46 in which a press pin 47 is operable. A spring 48 reacts between the outer end of the sleeve portion 46 and a flange 49 on the press pin 47 to normally urge the press pin outwardly through an opening 50 in the cover plate 25. This press pin has a bottom slot 51 for receiving the upper end of the operating member 33. The operating member 33, under the action of the springs 38 and 39 will move upwardly into the slot 51 when the press pin is pushed inwardly whereby to cause the projection 42 of the squared opening member 41 to enter the opening 43 of the operating member 33, in the manner as shown in Fig. 6, and to thereby prevent the turning of the squared shaft 13 and the outside knob 16. In order to release the press pin 37, the inside knob 14 must be turned so that the cam 28 on the sleeve piece 27 pushes downwardly the operating member 33, in the manner illustrated in Fig. 5, so that the squared opening member 41 and its projection 42 is released from the opening 43 of the operating member 33.

In use, the door 10 is closed and from the inside of the room, the press pin 47 is pushed inwardly. The pressing of this pin permits the operating member 33 to rise and the shaft and outside knob to be locked against turning movement. It is now impossible to enter the room from the outside. Automatically, as the inside knob 14 is turned, the press pin 47 will be released so that it will thereafter hold down the operating member 33 so that the squared member 41 on the shaft 13 will be released from the operating member 33 and both knobs again free to turn. When the knob assembly is locked, the outside knob cannot be turned until the assembly has been released by the turning of the inside knob.

It will be apparent that there has been provided a simple arrangement for locking and unlocking doors on their inner sides thereof.

While various changes may be made in the detail construction, it shall be understood that such changes shall be within the spirit and scope of the present invention as defined by the appended claims.

I claim:

1. A door latch assembly adapted to be latched from the inside by means of a press-pin and unlatched from the inside by rotation of the inside doorknob, comprising a shaft having a square portion and a round portion, said round portion having a pin permanently secured therein, a sleeve piece having an orifice therethrough and

having a circular flange head and a threaded tubular portion secured to said flange head, said flange head having a slot depending from the orifice of said sleeve piece and a cam disposed above said slot and secured to that flange face which is opposed to the threaded portion of said sleeve piece, said cam being a segment of an annulus having radial edges converging to the center of said sleeve piece, a closure plate having an orifice therein adapted to receive the threaded portion of the said sleeve piece, and having parallel spaced-apart ribs therein, said guide ribs having oppositely and inwardly disposed guide portions, a vertical slide member adapted to slide between the ribs of the closure plate, said slide member consisting of a pair of vertical parallel walls and a pair of horizontal parallel walls, said horizontal parallel walls extending beyond said vertical walls, the lower horizontal wall having a slot therein disposed centrally thereof, said slide member further having a back plate secured to the lower half of said slide member and having a pair of spaced-apart legs having inverted V-shaped apices, the space between the said legs being of a U-shape, the slide member being disposed within the ribs of the closure plate so that the lower horizontal wall is disposed beneath the guide portions of said closure plate, said guide portions being abutments to limit the upward travel of the slide member, means disposed between the spaced-apart ribs and the slide member for urging said slide member in an upward direction, a square member having a square opening and provided with a depending leg disposed over a portion of the square shaft, said depending leg being adapted to move into and out of the slot in the lower horizontal wall of said slide member, a channeled retaining plate having a press-pin therein adapted to retain the slide member in place, said press-pin having a depending slot therein adapted to engage the top vertical wall of said slide member, said press-pin being normally outwardly urged by means of a spring associated therewith.

2. The latch assembly of claim 1 wherein the means for urging the slide member normally downward consists of a pair of spaced-apart springs disposed between the guide portions and the bottom of the extended portions of the top slide member wall, said springs being confined laterally between a vertical wall of the slide member and a rib of the closure plate.

MAX SULTAN.
